J. C. WHITE.

BUFFER STOP FOR FIREARMS.

APPLICATION FILED SEPT. 26, 1918. RENEWED AUG. 15, 1921.

1,410,436.

Patented Mar. 21, 1922.

UNITED STATES PATENT OFFICE.

JOSEPH C. WHITE, OF BOSTON, MASSACHUSETTS, ASSIGNOR TO WHITE-GREENMAN ARMS COMPANY, OF BOSTON, MASSACHUSETTS, A CORPORATION OF MASSACHUSETTS.

BUFFER STOP FOR FIREARMS.

1,410,436.

Specification of Letters Patent. Patented Mar. 21, 1922.

Original application filed November 12, 1917, Serial No. 201,484. Divided and this application filed September 26, 1918, Serial No. 255,786. Renewed August 15, 1921. Serial No. 492,634.

To all whom it may concern:

Be it known that I, JOSEPH C. WHITE, a citizen of the United States, and resident of Boston, county of Suffolk, Commonwealth of Massachusetts, have invented an Improvement in Buffer Stops for Firearms, of which the following description, in connection with the accompanying drawings, is a specification, like characters on the drawings representing like parts in each of the several views.

This invention relates to yielding buffers or stops for use in automatic or semi-automatic guns to afford a cushioned or resilient stop for the moving parts on the backward movement thereof resulting from the discharge of the gun; being a division of my prior application, Serial No. 201,484, filed November 12, 1917. While not limited thereto in its broader aspects, the invention is well adapted and designed for use with a gas operated automatic or semi-automatic gun wherein a portion of the discharge gases acts on a plunger member to reset the action. The foregoing and other objects and advantages of the invention will more fully appear from the following detailed description, and the distinctive features of novelty will be pointed out in the appended claims.

Referring to the drawings:

Fig. 1 is a view in horizontal section showing a portion of a gun and its receiver having my present improvements incorporated therewith;

Fig. 2 is a plan view of the same; and Fig. 3 is a transverse section on line 3—3 of Fig. 1.

The barrel of the gun is indicated at 10 with a firing chamber 11, and with a receiver 12 containing the operative parts of the action screwed to the barrel as usual as seen at 13. The breech bolt is indicated at 14 with a firing pin 15 operative therein, which breech bolt and firing pin constituting no part of the present invention need not be further described in detail. The receiver is equipped at its bottom with a suitable cartridge magazine 16 also not involved in the present invention. To the top of the receiver 12 is slidably fitted a saddle 17, this saddle being shown as interengaged with the receiver by the interlocking slots and ribs 18 at the opposite sides of the receiver. As shown the saddle 17 is equipped

with a projecting lug 19 which engages in a spiral slot 20 of the breech bolt thus constituting means for actuating the breech bolt from said saddle, and with it controlling the firing pin which is fitted in the breech bolt, in a manner that need not be specifically detailed herein. The invention is herein shown as embodied in a gas-operated type of gun and a portion of a gas cylinder is indicated at 21 extending alongside the gun barrel and receiving gas from a lateral port therein (not shown.) The piston rod of the piston operating in such cylinder is indicated at 22 guided through a bushing 23 at the inner end of the cylinder 21 and screw threaded as seen at 24 into a lug 25 formed with and projecting laterally from the saddle 17. This lug 25 is hollow and has threaded thereinto a hollowed out handle plug 26 which serves as a housing for a spring pressed plunger pin 27 fitted into the hollow thereof, this pin having a reduced stem 28 around which is mounted a coil spring 29 to react against the head of said pin. The head of the spring pressed pin 27 is thus projected into a slot 30 extending lengthwise in the side of the receiver and for a distance corresponding to the range of movement of the saddle 17. In accordance with my invention the head of the plunger pin 27 is beveled off on its rear side as indicated at 31 at approximately a forty-five degree angle, and the rear end of the slot 30 is formed with a correspondingly beveled wall 32, this wall being so located that it is encountered by the beveled face 31 of the pin just before the saddle reaches the backward limit of its movement. Thus the plunger pin 31 will offer a yielding resistance to the further backward movement of the saddle and serve as a cushion stop or resilient buffer preventing or minimizing concussion or hammer blow reaction of the saddle as it reaches the limit of its backward movement on its actuation by the gas at discharge, which actuation it will be understood is at a relatively high rate of speed so that the taking up of this concussion action becomes a feature of importance and significance. In practice the spring 29 will be made strong enough in proportion to the reactive force of the saddle, so that the residue of such force will be taken up and absorbed by the spring

pressed plunger pin on a partial outward movement only thereof so that the pin 27 is never pressed fully out of the slot 30. The handle plug 26 is extended outward to 5 constitute a hand hold 26^a for drawing back the saddle by hand when required. I am aware that the invention may be embodied in other specific forms without departing from the spirit or essential attributes thereof, and I therefore desire the present embodiment to be considered in all respects as 10 illustrative and not restrictive, reference being had to the appended claims rather than to the foregoing description to indicate the 15 scope of the invention.

Having described my invention, what I claim as new and desire to secure by Letters Patent is:

1. In a firearm, a receiver, a saddle slidably fitted thereon and constituting an operating member for the action of the gun, and cooperative means on said saddle and receiver to form a yielding buffer to stop the saddle on its backward movement, said 20 means consisting in a spring pressed bevel faced element on one of said members engaging a beveled face on the other of said members.

2. In a firearm, a receiver, a saddle slidably fitted thereto and constituting the operating

element of the gun action, and a yielding buffer for said saddle to cushion its backward movement, consisting in a spring pressed pin carried thereby, equipped with a beveled rear face and fitting into a lengthwise slot 35 in said receiver having a cooperative beveled face at the rear end thereof.

3. In a firearm, a receiver, a saddle slidably fitted thereto and constituting the operating element of the gun action, a yielding buffer for said saddle to cushion its backward movement, consisting in a spring pressed pin carried thereby, equipped with a beveled rear face and fitting into a lengthwise slot 40 in said receiver having a cooperative beveled face at the rear end thereof.

4. In a firearm, a receiver, a saddle slidably fitted thereon and constituting an operating member for the action of the gun, a laterally extending hand piece borne by said saddle, and a spring pressed buffer member housed in said hand piece and presenting a beveled face co-operative with a relatively 50 fixed surface of the receiver for the purpose stated.

In testimony whereof I have signed my name to this specification.

JOSEPH C. WHITE.
